UNITED STATES PATENT OFFICE.

WILLIAM M. VENABLE, OF PITTSBURGH, PENNSYLVANIA, ASSIGNOR TO BLOW-KNOX COMPANY, A CORPORATION OF NEW JERSEY.

HOISTING-DERRICK.

1,376,054.

Specification of Letters Patent. Patented Apr. 26, 1921.

Application filed October 2, 1918. Serial No. 256,491.

To all whom it may concern:

Be it known that I, WILLIAM M. VENABLE, a citizen of the United States, residing at Pittsburgh, in the county of Allegheny and State of Pennsylvania, have invented certain new and useful Improvements in Hoisting-Derricks, of which the following is a specification.

My invention has for one of its primary objects to provide an improved derrick designed to operate in a very efficient manner a single line clamshell or grab bucket, such, for instance, as that described in my Patent No. 1,258,883, and in my co-pending application, Serial Number 242,736, though its range of service may be readily extended to include other buckets, or other load receiving devices, especially in the latter instance if suitable hoisting block and bail be employed. Another object of the invention is to improve and simplify the construction and increase the efficiency and utility of apparatus of this character. Further objects are to provide an improved apparatus capable of adaptation to a wide range of use; and to provide a simplified and efficient means of control for the boom and the bucket carried by the boom.

A still further object is the provision of a derrick operated by power furnished by a single hoisting drum driven by any ordinary non-reversing hoisting engine or motor, wherein the bucket with its load is first hoisted vertically and then swung away in the direction of the length of the boom to the unloading point, the bucket being returned in a supported relation to the original position at the will of the operator, and both bucket and boom being operated by a single operating cable under the complete control of the operator.

These, together with such other objects and advantages hereinafter described and set forth, or are incident to my invention, I attain by means of a construction illustrated in preferred form in the accompanying drawings wherein—

Figure 1 is a view in side elevation of my improved derrick, the figure illustrating possible operative positions of boom and bucket, and,

Fig. 2 is an enlarged detailed drawing illustrating a desirable form of clutching means on the mast for holding the boom in any desired operative position.

Referring to the drawings, the reference character A denotes a mast which, at a suitable distance from its base, is formed with an opening 4. Through this opening the boom B is designed to oscillate back and forth in the direction of its length, in order that the bucket C may be moved between its operative positions, at which points the bucket is intended to be actuated by the same means that imparts movement to the boom.

The outer end of the boom is stayed to the top of the mast by the line 5, and its body portion, desirably throughout the major part thereof, is formed with an elongated slot 6 through which the pivot pin 7 extends to have its ends 7^a and 7^b terminally carried by the spaced side walls a, a, of the mast at the sides of the opening 4. In the preferred construction illustrated in Fig. 2, clamping elements 8, 8, are positioned on the pin to grip the sides of the boom upon actuation of the hand lever 9, by the tightening of which the boom may be held and supported in a fixed position with reference to the mast. Hubs or bearings 10 are provided for the pin, the end 7^b having a screw threaded engagement with one hub and the end 7^a extending through the other hub to terminally receive the hand lever 9, which latter upon being actuated tightens or releases the clamping elements.

The means for imparting longitudinal movement to the boom B will now be described. Near the ends of the slot 6 are journaled the sheaves 12 and 13, respectively, and in the opening 4, below the pin 7, is a similar sheave 11. The reference character D designates a drum, which may be driven by any ordinary non-reversing hoisting engine or motor (not shown), and to which is fastened and wound about a hoisting or operating cable 14. From the drum this cable passes over the sheaves 11, 12 and 13, through the bucket B to the outer end of the boom where it is made fast, as shown at 16.

In order to provide a support for the bucket, or other load receiving device, during boom movement, the boom is provided near its outer end with a pivoted hook member 15 adapted to hook the bucket or such portion of the bucket as the bucket supporting bail 17. This hook has a lifting lever arm provided with a line which passes over a sheave 18 on the top of the mast and

terminates in a handle 19, the clutch lever being similarly provided with a handle 20, if desired. Obviously, by exerting a pull on handle 19 the hook may be retracted out 5 of the way of, or disengaged from, the bucket. Similarly, a pull on handle 20 will tighten the clamps and fixedly position the boom, and opposite movement will release them and permit the travel of the boom between such positions as are indicated in full 10 and dotted lines in Fig. 1.

The operation of the apparatus is substantially as follows. With the boom clamped and positioned as indicated in dotted lines in Fig. 1, the hook 15 is retracted and disengaged from the bucket by exerting a pull on the handle 19. The bucket may then be lowered to obtain its load by slackening the line, which slack is paid out 15 gradually when the engine is thrown out of engagement with the drum. With the drum in a drive relation, the bucket may then be hoisted by the cable 14 until it engages the hook, whereupon the bucket again 20 assumes the dotted position shown. The clutch is then released, and upon a further winding of the cable on the drum endwise movement is imparted to the boom until the bucket is advanced toward that position 25 where it is desired to release the load. During this movement the bucket is held in a supported relation independently of the cable. When the unloading position is 30 reached, the clamp is tightened, and the bucket opened in the usual manner, as by a trip lever (not shown). Should it be necessary in this unloading operation to lower the bucket the hook may be readily disengaged therefrom by exerting a pull on handle 19, and the line 14 slackened to accommodate the movement. In other words, during 35 the travel of the bucket toward or away from the mast the clamp is loosened to disengage from the boom, and is tightened during vertical bucket movement so that the action of the line is without influence on the boom at that time.

The apparatus is adapted to a wide range of use, and it is easily constructed and set up, there being an entire lack in the apparatus of any involved or expensive parts. It may be readily used in loading and unloading cars of bulk materials, for which purpose it is particularly adapted. Obviously, 50 the mast may be stationary or rotatable, or again, it may just as well be mounted upon a turntable so as to face in a plurality of directions as desired, without in any way affecting or restricting the operation of the apparatus as above set forth and described.

Furthermore, it may be employed in excavating trenches for sewers, or in excavating and cleaning out vertical pits or shafts for mines or tunnels. In the former case the

mast may be positioned on a car running at 65 one side of the trench, or astride of it or backing away from it, and the material delivered in the desired direction by properly facing the mast that way; and in the latter instance the mast may be placed at the side 70 of the shaft and the material delivered at an elevation on the opposite side.

From the foregoing, the essential elements and features of the apparatus, together with its simplicity and other advantages thereof, 75 will be readily apparent to those skilled in the art.

I do not intend to restrict myself to the exact details of construction, or to the precise arrangement of the parts, as shown, as 80 it is obvious that modifications thereof may be made without in any way departing from the spirit and scope of my invention as pointed out in the appended claims.

What I claim is:

1. A derrick comprising in combination, a mast provided with an opening, a boom mounted in the opening for longitudinal movement with respect to the mast, braking means on the mast and disposed in said opening adapted to releasably hold the boom at any position against longitudinal movement in either direction, and cable operating means for the boom.

2. A derrick comprising in combination, a mast, a boom mounted thereon for longitudinal movement with respect thereto, braking means on the mast adapted to releasably engage and hold the boom at any position against movement in either direction, a load 100 receiving device associated with the boom, sheaves on the mast, boom, and load receiving device, and a single operating cable for the boom and the load receiving device reeved on the sheaves and having one end 105 fastened at substantially the outer end of the boom.

3. A derrick comprising in combination, a mast, a boom mounted thereon for longitudinal movement with respect thereto, braking means on the mast adapted to releasably engage and hold the boom at any position against movement in either direction, and cable operating means for the boom.

4. A derrick comprising in combination, a mast, a boom mounted thereon for longitudinal movement with respect thereto, holding means adapted to releasably hold the boom at any position against movement 120 in either direction, a grab bucket associated with the boom, and a single cable adapted to operate the bucket and to move the boom.

5. A derrick comprising in combination, a mast, a boom mounted thereon for longitudinal movement with respect thereto, cable operating means for the boom, and holding means adapted to releasably hold the

boom at any position against movement in either direction independently of the operating cable.

6. In a derrick, the combination of a support provided with a releasable clutch, a boom pivot pin associated therewith, a slotted boom normally carried near one end by said clutch and capable of oscillatory movement on said pin relatively to the support to vary the length of the boom when released from said clutch, sheaves on said boom and said support, a stay connection between the other end of the boom and the support, and an operating cable for the boom reeved about said sheaves.

7. In an apparatus of the character described, the combination with a grab bucket having an operating cable, of a movable boom provided with sheaves near its inner and outer ends and formed intermediately with a slot, a support or mast having a sheave and provided with means for sup-

porting said boom in variable shortened or lengthened operative positions, part of said means operating in said slot during movement of the boom between its operative positions, said cable coöperating with said sheaves and capable of imparting movement to said boom, and means independent of said cable for supporting the bucket during boom movement.

8. In an apparatus of the character described, the combination of a mast, and a boom arranged to swing back and forth relatively to and through said mast, said mast provided with means adapted to releasably hold and support said boom in a plurality of operative positions, and means reeved on said boom and mast for imparting such swinging movement to the boom, the latter in one of its positions having its outer end nearer the mast than its inner end.

WILLIAM M. VENABLE.
